UNITED STATES PATENT OFFICE

106,423

DESIGN FOR A REPLACEMENT BATTERY CARRIER

Ernest R. Brodeen, Chicago, Ill., assignor to B-G-H Automotive Manufacturing Company, a co-partnership consisting of Earl H. Gromer and Ernest R. Brodeen

Application August 2, 1937, Serial No. 70,804

Term of patent 7 years

To all whom it may concern:

Be it known that I, Ernest R. Brodeen, a citizen of the United States, residing at Chicago, in the county of Cook and State of Illinois, have invented a new, original, and ornamental Design for Replacement Battery Carrier, of which the following is a specification, reference being had to the accompanying drawing, forming a part thereof.

On the drawing:

Fig. 1 is a front perspective view of my new design for a replacement battery carrier; and
Fig. 2 is a plan view thereof.

I claim:

The ornamental design for a replacement battery carrier, as shown.

ERNEST R. BRODEEN.
